UNITED STATES PATENT OFFICE.

ZACHARIAH ALLEN, OF PROVIDENCE, RHODE ISLAND.

COUNTERPANE.

Specification of Letters Patent No. 9,962, dated August 23, 1853.

To all whom it may concern:

Be it known that I, ZACHARIAH ALLEN, of the city and county of Providence and State of Rhode Island, have invented a new and 5 useful Counterpane, of which the following is a full, clear, and exact description, reference being had to the accompanying drawing of the same, which makes part of this specification, and in which—

10 Figure 1 represents a view of a fragment of a counterpane outspread upon a flat surface, and Fig. 2 is a transverse section of the same upon an enlarged scale at the line xx of Fig. 1 and Figs. 3 and 4 are sections 15 of counterpanes made with cords and threads of a greater diversity of sizes.

It has long been an acknowledged desideratum to produce a woven cotton counterpane, as ornamental and durable as the 20 Marseilles quilt or counterpane and at little if any greater price than a common calico sheet of the same size, weight, and quality of material, so that while it would be sufficiently neat and ornamental to adapt it to 25 the tastes and use of the rich, its price will be so low as to bring it within the reach of all who can afford to maintain a bed.

The object of my present invention is to supply this desideratum, and it consists in 30 weaving cloth of a width equal to the length required for a counterpane, the weft of the cloth being composed of cord and thread woven in alternate order, the thread being the usual size for the warp employed, and 35 the cord considerably thicker, the different wefts being so woven as to form a ribbed surface. The thickness and twist of the cord should be such, that when woven its tension and rigidity will produce kinks by 40 its tendency to untwist that will form helicoidal curves, and give to the ribs a wavy or undulating surface, which adds greatly to the beauty of the fabric, producing a unique appearance, and constituting a new 45 article of manufacture. This fabric is produced by weaving in the usual manner in any loom fitted to throw in alternate order a series of shuttles as numerous as the different sizes of thread and cord employed to 50 fill in one pick of weft each, or so that each will fill in several consecutive picks of weft before the next is brought into operation, as the relative width of the ribs to form any given pattern may require.

55 As any competent loom builder would be

capable of constructing, mounting and operating a loom to produce such a fabric as I have here described, it is not necessary to embody directions in regard to the details of the machinery of the loom in this specification; I shall therefore merely describe the manner in which the weft, threads and cords of counterpanes of the pattern represented in the drawing are arranged.

In Figs. 1 and 2, the warp threads (a) 60 are of the kind usually employed for weaving plain cotton sheeting, and consequently whenever the common weft thread (b) is employed, a rib of plain cloth is made—whenever the cord (c) is thrown a strip or 65 rib of thicker cloth is made. The broad rib 1 is composed of six thick weft cords; and the narrow rib 2 is composed of two cords. The strips 5 and 7, of common cloth contain 70 respectively twenty, and four threads of 75 weft; and the two shuttles which this sample of the fabric requires in weaving, one for the thick, and the other for the small filling, will be thrown a number of times 80 corresponding to the relative number of threads of the different kinds used to form the respective ribs or strips of this pattern.

The threads and the cords of the weft 85 may each be of different sizes so as to form gradually swelling ribs, if it should be for any cause deemed advisable to make the ribs in this way. An example of two of these modifications of the ribs is represented in Figs. 3 and 4.

After the web has been woven in this 90 manner, it is divided transversely by cuts parallel to the strips into lengths equal to the width it is required to make the counterpanes; each counterpane thus cut off, will have a selvage at its ends and will require hemming at the sides.

What I claim is—

The ribbed counterpane herein described as a new manufacture, it being so made that the thickness and twist of the cords forming 100 the ribs on the same by their tendency to untwist will give to the said ribs a wavy or undulating surface as herein set forth.

In testimony whereof I have hereunto subscribed my name.

Z. ALLEN.
